UNITED STATES PATENT OFFICE.

CHARLES BREARLEY MOORE, OF EVANSTON, ILLINOIS.

ARCH FOR LOCOMOTIVE-FURNACES.

No. 904,494.

Specification of Letters Patent.

Patented Nov. 17, 1908.

Original applications filed May 20, 1907, Serial Nos. 374,721 and 374,722. Divided and this application filed July 10, 1908. Serial No. 442,979.

To all whom it may concern:

Be it known that I, CHARLES BREARLEY MOORE, a citizen of the United States, and resident of Evanston, Cook county, Illinois, 5 have invented certain new, useful, and Improved Arches for Locomotive-Furnaces, of which the following is a full, clear, and exact description, such as will enable others skilled in the art to which it appertains to 10 make and use the same.

This is a divisional application, the subject matter hereof having been previously disclosed in my pending applications, filed May 20, 1907, Serial Numbers 374,721, and 15 374,722.

My invention relates to improvements in locomotive boiler furnaces and has for its object the improvement of the form, construction and arrangement of refractory 20 brick arches for and in locomotive boiler fire boxes of the kind which are equipped with arch supporting tubes.

Special objects and advantages of my invention will appear hereinafter.

25 My invention consists in a locomotive firebox, equipped with arch supporting tubes; in combination with an arch body composed of refractory bricks, resting upon said tubes and approaching the sides of the firebox; 30 and, wing, marginal or wedging bricks which rest against the respective sides of the firebox in the spaces between the arch body and said sides; all as, and for the purposes, 35 hereinafter specified and particularly pointed out in the appended claims.

My invention will be more readily understood by reference to the accompanying drawings forming part of this specification, and in which,

40 Figure 1, is a vertical section of a locomotive fire box of the "wide" type, containing a refractory front arch embodying my invention, the section being on the irregular line X—X of Fig. 2. Fig. 2, is a horizontal section on the line Y—Y of Fig. 1. Fig. 45 1, is a vertical section on the lines Z—Z of Figs. 1 and 2. Fig. 4, is a sectional detail, substantially on the line V—V of Fig. 1. Fig. 5, is a vertical section of a locomotive fire 50 box of the "narrow" type, containing an arch of my invention, the section being on the line W—W of Fig. 6. Fig. 6, is a horizontal section on the line U—U of Fig. 5. Fig. 7, is a vertical section on the line T—T

of Figs. 5 and 6. Fig. 8, is a sectional detail 55 on the line S—S of Fig. 5.

As shown in the drawings the walls of a locomotive fire box are constituted by the flue sheet 2; the side sheets 3, 3; the rear sheet 4 and the crown sheet 5.

60 6 represents the grate. The flues 7, extend forward from the upper part of the flue sheet 2. The fire box is inclosed by the boiler shell and forms therewith the usual front, side and rear water legs 8", 8' and 8. 65 The arch tubes 9 occupy inclined positions and extend from the lower part of the flue sheet 2, to the upper part of the rear sheet, 4. The water from the front water leg 8" flows through the tubes to the rear water leg 8 70 and prevents the burning out of the tubes. Fire boxes of different types and sizes require arch tubes of different forms and inclinations, also different numbers thereof; but they are essentially the same, and perform 75 the same functions, in all cases. Locomotive fire boxes are of two principal types; the "wide" type and the "narrow" type. Fire boxes of the "wide" type, as shown in Figs. 1 to 4, are characterized by side sheets which 80 are substantially vertical or which flare outwardly at the bottom, the grate, generally, being of practically the same width as the top of the fire box. "Narrow" fire boxes as shown in Figs. 5 to 7, are characterized 85 by side sheets which curve or flare inwardly at the bottom, their grates being narrower.

Notwithstanding the different shapes, to avoid confusion, I have applied the same reference numerals to corresponding parts 90 throughout the drawings of both the "wide" and the "narrow" fire boxes.

95 My invention as herein represented is readily adaptable to all types and sizes of locomotive fire boxes and overcomes the difficulties met with, and the objections hitherto urged against the use of, arch tubes and refractory arches in locomotives, including such as are common to all types as well as the objections and difficulties that are individually characteristic thereof.

100 The arch rests upon the arch tubes and is composed of a number of refractory bricks; these take their dimensions from the fuel door of the fire box, through which they must be passed if the removal of the grate is to be avoided. In fact larger bricks are too heavy for convenient handling and it

is desirable that they be as small as here indicated.

In carrying out the invention I employ as many arch tubes as may be required to suit 5 the dimensions of the bricks and the dimensions of the fire box. In placing the arch tubes in the fire box I space them to correspond with the width of the bricks and I leave, between the outermost tubes and the 10 side sheets, sufficient space to permit easy access to the side sheets and the stay bolts, which require frequent inspection and repair.

My novel arch comprises a body portion or arch proper A, and marginal, wing or 15 locking portions B. I generally make the body portion laterally co-extensive with the group of arch tubes and the effective widths of the wing bricks are greater than the spaces which remain between the edges of 20 the arch proper and the side sheets. The body portion or arch proper A, is made up of one or more footing bricks a' , which rest upon the arch tubes and against the flue sheet, together with one or more longitudinal 25 rows of body bricks a^2 , which lie on the tubes and against the footing bricks. As shown, I prefer that the footing bricks a' shall be of less width than the lower part of the fire box, but of greater width than the 30 upper part of the arch proper, to the end that the projecting ends of the footing bricks may serve to support the wings B. When the arch is thus constructed it is unnecessary to shape the lower ends of the 35 wings or otherwise fit them against the flue sheet. Although the body of the arch is composed of a number of bricks and in the larger fire boxes may comprise several transverse and longitudinal rows thereof, it may 40 be referred to as a single body, and in this sense may be described as having beveled longitudinal edges a^3 adjacent to respective side sheets. These beveled surfaces overlie the outermost arch tubes and in forming the 45 edges of the arch in this manner one purpose is to provide broad bearing surfaces for the wings, key or wedging members B. These bricks or locking members B are substantially wedge shaped in cross section, having 50 relatively inclined edge surfaces or ends b' and b^2 , and they fit the wedge shaped openings or spaces defined by the side sheets of the furnace and the inclined edges a^4 of the arch body.

55 As clearly shown by Figs. 2 and 6, the edges of the arch are parallel or substantially parallel, and the outer edges of the wings B, are shaped to substantially conform to the side sheets of the furnace. For 60 "wide" fire boxes I employ several wing or locking bricks b^3 of uniform shape, having edges which are substantially parallel, whereas in adapting my invention to "narrow" fire boxes, I find it desirable to employ wing 65 bricks b^4 , which increase in width towards

the top. The bricks b^3 are interchangeable in the wide or straight sided fire boxes, the spaces on opposite sides of the arch being of the same length and breadth. In like manner the bricks b^4 are made interchangeable 70 in narrow boxes by providing the inner edges or ends thereof with beveled surfaces b^5 , either of which may be placed against the inclined edge of the arch body. The wing or key bricks break joints with the arch 75 bricks and each wing brick thus engages the ends of at least two body bricks a^2 . The body bricks are thus effectually locked against relative transverse movement on the arch tubes. 80

One of the objects of my invention is to avoid the use of brick supporting lugs on the side sheets, and a further object is to provide an arch which will be self-tightened by the vibration of the locomotive. The wing 85 bricks B are of greater width than the spaces between the side sheets and the edges of the arch and when dropped into place are supported by the side sheets without the aid of lugs thereon. They also tend to wedge 90 themselves tightly between the arch and the side sheets and therefore complete an arch structure which is very rigid and which fits so tightly between the side sheets that it cannot move laterally between them or on the 95 tubes. When placed in a fire box of slightly less than the expected width, the wing bricks occupy somewhat more inclined positions than shown in the drawings, and when a somewhat wider box is fitted the bricks B 100 may drop substantially into the plane of the arch body, and yet securely wedge and lock the body bricks in place upon the tubes. To reduce the surface contact between the side sheets and the wing bricks B, I preferably 105 scallop or notch, i. e. point the edges or ends of the latter, and thus provide each thereof with one or more projections b^6 . A further advantage of these projections is that being of small size they may be readily cut or 110 chipped off to fit a warped or patched side sheet.

As various modifications of my invention will readily suggest themselves to one skilled in the art I do not confine or limit the invention to the specific shapes, structures or arrangements of bricks herein shown and described. 115

Having thus described my invention, I claim as new and desire to secure by Letters 120 Patent:—

1. A locomotive boiler firebox or furnace, in combination with a group of arch tubes of less width than said furnace, a refractory arch laterally co-extensive with said group 125 of arch tubes and resting thereon, and wedge shaped bricks closing the spaces between the edges of said arch and respective sides of the furnace, substantially as described.

2. A locomotive boiler furnace in combi- 130

nation with a group of arch tubes of less width than said furnace, a refractory front arch laterally co-extensive with said group of arch tubes and resting thereon, and side 5 or marginal members also supported by the outer arch tubes and resting against and supported by the sides of the furnace, in the spaces between the edges of said arch and the sides of the furnace, substantially 10 as described.

3. A locomotive boiler furnace having arch tubes in combination with a refractory arch of less width than said furnace and arranged upon said arch tubes and members 15 of greater width than the spaces between said arch and the sides of the furnace and acting after the manner of wedges to secure the arch between the sides of the furnace, substantially as described.

20 4. A locomotive boiler furnace equipped with arch tubes in combination with a refractory brick arch supported by said tubes and of less width than said furnace, and upwardly and outwardly inclined refractory 25 bricks resting upon and supported by respective edges of the arch and sides of the furnace, as and for the purpose specified.

5. A locomotive boiler furnace and its flue sheet in combination with a group of inclined arch tubes, of less width than said furnace, a refractory arch abutting the flue sheet and comprising a suitably supported body portion laterally co-extensive with said group of arch tubes, and side portions of 35 greater width than the spaces between said body portion and the sides of the furnace, said side portions leaning against and being supported by said sides, substantially as described.

40 6. A locomotive boiler furnace and its flue sheet in combination with a group of arch tubes, of less width than said furnace, a refractory arch abutting said flue sheet and comprising a body portion, laterally co-extensive with said group of arch tubes and provided with upwardly and inwardly inclined beveled edges, and marginal bricks of 45 greater width than the spaces between said body portion and the sides of the furnace, resting upon and supported by said beveled edges and said sides, substantially as described.

7. A locomotive boiler furnace, in combination with a group of arch tubes of less 55 width than said furnace, an arch body formed of a plurality of refractory bricks, supported by said tubes, said arch body being substantially laterally co-extensive with said group of arch tubes, and wedge shaped 60 members arranged between the edges of said arch and the sides of said furnace, substantially as described.

8. A locomotive furnace having arch tubes, in combination with a refractory arch resting thereon and comprising transverse foot- 65

ing bricks abutting the end of the furnace and an upper portion composed of longitudinal rows of bricks rising from said footing bricks, said upper portion being of less width than the furnace, and bricks of greater 70 width than the spaces between said body portion and the sides of the furnace also rising from said footing bricks and adapted to close said spaces and wedgingly lock the whole in place upon the arch tubes, substantially as described. 75

9. A locomotive boiler furnace having inclined arch tubes, in combination with an arch arranged upon said tubes and comprising a body portion composed of longitudinal 80 rows of bricks resting on said tubes and upwardly and outwardly inclined members, acting as wedges and locking said body portion upon said tubes and between the sides of the furnace, substantially as described. 85

10. A locomotive boiler furnace, having arch tubes, in combination with a refractory arch resting upon said tubes and comprising a body or central portion of less width than said furnace and wedgelike closures for the 90 spaces between said central portion and the sides of the furnace, said closures comprising a plurality of bricks having a plurality of projections contacting the sides of the furnace, subsequently as described. 95

11. A locomotive boiler furnace, in combination with a refractory front arch of less width than said furnace, arch tubes arranged beneath the edges of said arch, and wedge like closure members of greater width than 100 the spaces between said arch and the sides of the furnace and supported therebetween, the inner edges of said closure members resting upon the edges of said arch, substantially above said arch tubes, substantially as described. 105

12. A locomotive boiler furnace having inclined arch tubes in combination with a refractory arch comprising a central portion of less width than said furnace, supported 110 upon said arch tubes, and provided with upwardly and inwardly inclined beveled edges, the outer arch tubes being arranged substantially beneath the edges of said central portion, and key bricks of greater width than 115 the spaces between said central portion and the side sheets of the furnace, supported by said beveled edges and said side sheets, substantially as described.

13. A locomotive boiler furnace having 120 arch tubes, in combination with an arch formed of a plurality of rows of refractory bricks, said arch being of less width than said furnace and supported by said arch tubes, wedge shaped bricks arranged between the edges of said arch and the sides of the furnace, the joints between the several rows of bricks being substantially above respective arch tubes throughout, substantially as and for the purpose specified. 130

14. A locomotive boiler furnace containing a group of arch tubes, in combination with an arch comprising a transverse row of lower front bricks abutting the front end 5 of the furnace and a body portion composed of longitudinal rows of bricks rising from said lower bricks, said body portion being of less width than the furnace and supported by said arch tubes, said group of arch tubes 10 being laterally co-extensive with said body portion, and wedge bricks of greater width than the spaces between said body portion and the sides of the furnace, said wedge bricks resting on said body portion, substantially 15 as described.

15. A locomotive boiler furnace having longitudinally disposed arch tubes in combination with an arch arranged therein and comprising a transverse row of lower front 20 bricks, a body portion composed of longitudinal rows of bricks resting on said lower bricks, and upwardly and outwardly inclined rows of key bricks between said body portion and the walls of the furnace, substantially 25 as described.

16. A locomotive furnace in combination with an upwardly and rearwardly inclined refractory arch suitably supported therein, wing bricks extending between the edges of 30 said arch and adjacent sides of the furnace, said wing bricks serving to close the openings between the sides of the furnace and exerting wedging force upon the arch, thereby preventing lateral movement of the arch in 35 the furnace, substantially as described.

17. A locomotive boiler furnace in combination with an upwardly and rearwardly inclined refractory arch suitably supported therein, upwardly and outwardly inclined 40 refractory bricks extending between the edges of the arch and respective sides of the furnace and wedgingly locking the arch against lateral motion, substantially as described.

18. A locomotive boiler furnace containing a group of arch tubes in combination with a refractory arch body supported by said tubes and wing bricks extending between the edges 45 of the arch body and the adjacent sides of the furnace, said wing bricks exerting wedging force upon the arch body and thereby preventing lateral movement thereof in the furnace, substantially as described.

19. A locomotive boiler furnace in combination with an arch occupying an inclined position therein and comprising arch tubes and a plurality of refractory bricks supported thereby, and refractory, wedging bricks resting against the edges of the arch 55 and the sides of the furnace, substantially as described.

20. A locomotive boiler furnace, its flue sheets and side sheets, in combination with an arch occupying an inclined position in 60 the furnace and abutting said flue sheet,

said arch comprising a plurality of longitudinally arranged arch tubes and a plurality of refractory bricks supported thereby and wedge bricks occupying the spaces between the edges of the arch and said side sheets 70 and exerting wedging force thereon, substantially as described.

21. A locomotive boiler furnace, its flue sheet and side sheets in combination with a plurality of longitudinally arranged arch 75 tubes, an arch body composed of a plurality of refractory bricks supported by and transversely movable upon said tubes and bricks of greater width than the spaces between the arch body and the side sheets, exerting wedging 80 force thereon to prevent movement of the arch body on said tubes, substantially as described.

22. A locomotive boiler furnace, its flue sheet and side sheets, in combination with a 85 plurality of longitudinally arranged inclined arch tubes, an arch body composed of a plurality of refractory bricks supported by and laterally movable upon said tubes and a plurality of wedge bricks extending between 90 the edges of the arch body and adjacent side sheets of the furnace, substantially as described.

23. A locomotive boiler furnace, its flue sheet and side sheets, in combination with a 95 group of longitudinally arranged arch tubes in said furnace, a refractory arch body of less width than the furnace and supported by said tubes and bricks of greater width than the spaces between the edges of the arch 100 body and said side sheets, said bricks resting against said side sheets and closing said spaces, substantially as described.

24. A locomotive boiler furnace, in combination with a group of arch tubes of less 105 width than said furnace a refractory arch laterally co-extensive with said group of arch tubes and resting thereon, and locking bricks extending between and supported by the edges of said arch and the sides of the furnace, substantially as described.

25. A locomotive boiler furnace, in combination with a group of arch tubes of less width than said furnace, a refractory front 115 arch laterally co-extensive with said group of arch tubes and resting thereon, and wedge shaped locking bricks inclined against the sides of the furnace and operating to wedge the arch between the sides of the furnace, substantially as described.

120
26. A locomotive boiler furnace having arch tubes, in combination with an arch of less width than said furnace and composed of a plurality of refractory bricks laid upon said arch tubes and upwardly and outwardly 125 inclined bricks resting against the sides of the furnace and each engaging the ends of two said bricks, substantially as described.

27. A locomotive boiler furnace, containing a group of arch tubes, in combination 130

with a refractory arch on said tubes and of less width than the furnace, a plurality of locking bricks at each edge of the arch, said bricks resting against the edges of the arch and being inclined against the sides of the furnace in such relation as to be tightened by the vibration thereof, substantially as described.

28. A locomotive boiler furnace containing a group of arch tubes, in combination with a refractory arch on said tubes and of less width than the furnace, a plurality of wedge bricks engaged with each edge of the arch and having points or projections engaged with respective sides of the furnace, substantially as described.

29. An arch locking brick for locomotive furnace arches, having relatively inclined ends or edges and one end or edge having a point or projection for engagement with a furnace side sheet, substantially as described.

30. A locomotive boiler furnace of the

wide type having substantially straight vertical side sheets, in combination with a group of inclined arch tubes in said furnace, a refractory arch body arranged upon and supported by said tubes and of less width than the furnace, a plurality of marginal bricks at each edge of the arch body and of greater width than the space between the arch body and the respective side sheets, said marginal bricks being in endwise abutment and occupying inclined positions and being adapted to exert wedging force upon the arch body to secure the same between said side sheets, substantially as described.

In testimony whereof, I have hereunto set my hand, this 23rd day of June, 1908, in the presence of two subscribing witnesses.

CHARLES BREARLEY MOORE.
